REVERSIBLE BRIEF CASE

Samuel L. Beder, New York, N. Y., assignor of
one-half to Irwin F. Mills Associates, New
York, N. Y.

Application April 5, 1946, Serial No. 659,961

2 Claims. (Cl. 150—1.6)

1

The present invention relates to improvements in bags and portfolios and more particularly to schoolbags and the like.

One of the objects thereof is to provide a simple, efficient and inexpensive device providing a pair of oppositely arranged box-like bags so shaped, arranged and functioning that they may more conveniently encase, expose and render accessible the book contents thereof.

A further object thereof is to provide a brief-case resembling school bag which is composed of a carrying member from which two separate compartments are suspended when a handle is grasped hold of for this purpose, the characteristic of such bag being that it may be carried about either with both compartments exposed for instant accessibility of their contents or else encased to conceal said compartments.

Another object thereof is to provide a novel form of handle grasped bag or case where opposing hinged compartments are provided in conjunction with a specially manipulatable closure for both compartments where the separate compartments are adapted to be foldably disposed so as to open out from each other with their contents exposed for removal and so as to be closed one against the other in such a manner that the compartments are sealed against accessibility, but in either case rendering the device capable of being carried about in brief-case fashion.

A still further object thereof is to provide a school bag or like luggage wherein a flexible hinge binding strip connected to a pair of oppositely arranged box-like bags serves the three fold purpose as a grip for said bags, as a hinge therefor enabling one to open and close on the other and as a closure for the open parts of said bags.

With the above and other objects in view my invention consists in the arrangement, combination and details of construction disclosed in the drawings and specification and then more particularly pointed out in the appended claims.

In the drawings, wherein similar reference characters designate similar parts throughout the respective views:

Figure 1 is a perspective view of my invention in one of its transformations.

Figure 2 is a perspective view of another of its transformations, and

Figure 3 is a perspective view of a third transformation thereof.

Referring to the drawings, which are merely illustrative of my invention I disclose the various parts thereof. There are a pair of oppositely arranged box-like bags of similar shape and construction arranged, like a book, to open and close upon each other as shown in the figures. An endless handle member is in the form of a loop having the oppositely arranged hand grip arms 1 and 1a respectively. Designed to hingedly con-

2

nect as well as to bind the box like bags together is a flexible strip of preferably leather material 2, being the central part of a length of flexible material the opposite end rectangular portions of which cover up so as to form backing for the outer faces of the rectangular box-like bags. This particular strip 2 bridges the inner open ends of the compartments 8 of the bags. It is seen that the edges 9a of the walls composing these compartments 8 terminate short of adjacent outer ends 11 and 12 confining these compartments in so that the terminates 13 and 14 of these end portions 11 and 12 project beyond the compartments or pockets. It will also be seen that the backing material 2 covers the entire outer edges of these end confining portions 11 and 12 except the projecting terminals 8a and 9a. The outermost ends of terminals 11 and 12 are rounded out at 13 for one compartment and 14 for the other. Walls 7 form the sides opposite to those sides of the bags which are secured to the backing material 2. In order to simulate the usual gathers of a leather brief case bag the relatively stout rigid bar-like end portions 8a and 9a of each bag are grooved out as at 15.

Secured with one end to each end portion 8a, 9a of each bag is a fastener bar 9 which has its main length projecting outwardly of the bag at right angles to end portions 8a, 9a. The two fastener bars at either end of the device carry complementary snap fasteners 10 or glove fasteners and they project in opposite directions when not interengaged to close the two bags. It will be understood that the bottoms of the compartments 8 are closed, and that the rounded edges 13, 14 of the end members 8a, 9a are unattached to the central intervening backing, binding strip 2.

The handle member has opposing parts slidably mounted in eyelet attached holes formed in the binding strip 2 so the handle may slide between both of the bags. 7 designates the outer narrow wall of the compartment of one bag, while 1a denotes the similar wall of the other bag. 4 designates the slit occurring between both bags when in closed relation as is shown in Figure 1. B designates school books or similar contents contained in the compartments of the bags.

With parts arranged in the manner described the operation of the device is as follows. The flexible binding strip 2 performs three functions to wit (1) it is a hinge means for either bag to move relatively to the other bag; (2) it is a cover for closing the open parts of both compartments of both bags, and (3) it is a binding strip and grip for carrying the device about from place to place. The two bags, being arranged in brief case fashion have three transformable positions: (a) that shown in Figure 1 where the compartments of both bags are in closed carrying posi-

tion; (b) that shown in Figure 3 where both compartments are in open, carrying position, and (c) that shown in Figure 2 where both bags are shown lying upon their sides with their hinging binding strip 2 in stretched flat relation. There is an envelope container 3 attached to each bag upon a wall thereof having the closure 3a.

Where all the parts are arranged as illustrated in Figure 1, the securing arms 9 will be closed one against the other in overlapping relation and the glove fastener elements 10 will interengage so as to close both bags and hold them against accidental separation. The binding strip is wrapped tightly around the rounded edges 13, 14 of the end members 8a and 9a, thereby closing the open ends of the compartments 8 of the bag and covering the book contents thereof. Arm 1 of the endless handle is available for grasping so that by taking hold of the same the device may be lifted and carried about just like a brief case which it closely resembles.

When it is desired to carry the device about with the compartments in open position as is shown in Figure 3 where the contents thereof may readily be removed from the compartments, the parts will be arranged as illustrated. This is accomplished by disconnecting fastener arms 9 from each other, next flopping down upon a table the bag on the left until it lies on its side with the bag on the right on its top; then flopping over the bag on top over to the left so it also lies on its side or back. The device then appears as is shown in Figure 2. Next, take hold of arm 1a of the handle, lift it so it slides upwardly in the eyelets 2b, then lift up both bags off the table until the two bags are suspended upon the binding strap 2 as shown in Figure 3 with their compartments open so the contents may readily be gotten to.

If the parts are in the position illustrated in Figure 3 and it is desired to position the same in the position shown in Figure 2, simply push out forcibly the inner walls of both bags so they fall down flat upon their sides. In this position the rounded ends of end portion 8a and 9a confront each other in separated relation and the two pockets or compartments are open, making it easy to remove the contents or to take out whatever is required because part of the books are exposed so their titles may be read while they still are contained in the jackets.

If it is desired to place the parts shown in Figure 3 into the the transformed position of Figure 1, take hold of the bag on the left and raise it, then roll the rounded ends 13 of the left bag over the binding strip 2 and continue folding it until the left bag overlies the right bag. Then flop both bags so they stand up upright upon the bottom of the compartments alongside of each other. In placing the left bag of Figure 3 on the top of the right bag the binding strip 2 is wrapped around the rounded edges 14 thereof. Take the fastener arms 9 and snap together their interengageable elements 10 to close the two bags in such upright position. Then take hold of arm 1 of the handle, lift the bags and carry them about.

I do not confine myself to the exact details of construction shown save as pointed out in the appended claims.

What I desire to claim is:

1. A device as described consisting of a pair of compartments formed from a flexible sheet having its opposite ends folded back and around so as to be looped over one side of said sheet, end members connected edgewise to said folded back looped portions of said sheet as well as to the mentioned side of the sheet for the purpose of forming the said compartments, the open parts of said compartments confronting each other as the sheet lies flat upon its opposite side, with their end members spaced out of contact, the medial portion of said sheet bridging the intervening space between the compartments, a pair of linearly separated holes formed in said sheet medial portion and an endless handle having opposing arms slidably projecting through said holes, said end members being reversely positionable about said sheet medial portion so as to assume an upright position either with the compartments open in one position, or closed by the overhanging medial portion in their reversed position, and means for detachably securing both compartments together in contiguous parallel relation.
2. A device as described consisting of a pair of compartments formed from a single flexible sheet folded back upon itself at its opposite ends to provide oppositely arranged loops, each looped portion furnishing opposite spaced apart sides of a compartment, rigid end strips closing the opposing ends of said compartments surmounting one side of the flexible sheet in spaced apart relation at their open ends, the ends of said strips, at the open ends of said compartments being rounded so as to fit the medial portion of said sheet and form a cover for the open ends of the compartments when the sheet is folded reversely about its medial portion, fastener elements carried by said end strips adapted to register when the compartments are disposed in parallel relation after said closing operation so as to interengage each other to hold both compartments in an adjacent, closed-compartment relationship, and an endless grip handle operatively adjustable in the sheet medial portion for the purpose of moving in one direction to support the compartments in upright open position, with respect to said sheet medial portion, and moveable in a counter direction, to support said compartments in upright closed position with the medial portion reversely folded.
